HOLLOW BUILDING BLOCK

James Roe, Chicago, Ill., assignor of one-half to
Albert Kahn, Chicago, Ill.

Application May 10, 1943, Serial No. 486,356

8 Claims. (Cl. 72—41)

This invention relates to the art of constructing walls of buildings and the like, and is particularly concerned with an improvement in the construction of hollow tiles or building units for the formation of building walls.

While the tiles or hollow blocks of the present invention may be used for many purposes, it is an object of the present invention to provide a construction unit which is applicable for exterior walls of a building and which is particularly applicable for partition walls of all types of buildings, and which construction unit shall be of a minimum weight for the purpose. The building unit of the present invention is hollow and preferably, although not necessarily, of a generally rectangular shape.

It is a further object of the present invention to provide a building unit of such a shape that it can be formed by extrusion whereby it may be manufactured in any lengths desired. Standard types of joints, corners and other fittings are provided for attachment to the building unit. The building unit itself is preferably made of such material that may be sawed on the job to the requisite length, if it is necessary to reduce the length of a unit.

In the preferred embodiment of the present invention the unit is made of non-hygroscopic plastic, which may be cut by an ordinary sawing operation, similar to the way in which wood is cut. Any suitable thermo-plastic, thermo-setting, or synthetic resin material, having the desired strength, durability, weather resisting properties, heat and fire resisting properties, and aesthetic appearance may be used. The walls of the hollow unit may be made very thin where the unit does not have to support any substantial load. If the unit is to be used in a building wall that is subjected to appreciable compressive loads then the unit may be provided on the inside with one or more stiffening or load sustaining members which will carry the load to which the unit is subjected.

The fitting elements, joints and the like, are preferably attached to the body element by means of a sleeve that extends into and fits snugly within the main body element. Where the plastic element is a thermo-plastic material the joints may be permanently locked together by welding, as by applying heat to force some of the material of the body element into recesses provided therefor in the sleeve.

The attainment of the above and further objects of the present invention will be apparent from the following specification taken in con-

junction with the accompanying drawings forming a part thereof.

In the drawings:

Figure 1 is a view of a front wall of a building, partially broken away to illustrate the interior construction;

Figure 2 is a perspective view of a building unit of the present invention, joined at one end to a window jamb;

10 Figure 3 is a perspective view of a coupling or joining element;

Figure 4 is a transverse sectional view taken along the line 4—4 of Figure 2 and looking in the direction of the arrows;

15 Figure 5 is a perspective view of a building unit of the present invention with a joining element secured in one end thereof;

Figure 6 is a perspective view of a corner fitting for use with the building element of the 20 present invention;

Figure 7 is a sectional view of a unit of the present invention and illustrating the manner of positioning the reinforcing elements in place;

Figure 8 is a sectional view through a modified corner element joining units of the present 25 invention; and

Figure 9 is a transverse sectional view of a building element for use on cornices or the like.

Reference may now be had more particularly 30 to the accompanying drawings in which the same reference numerals designate the same parts in all the views.

In carrying out the present invention there are 35 a number of elements or units necessary for the construction of the desired walls. These elements consist essentially of the hollow tiles or building blocks which constitute the main part of the building wall, the coupling elements for coupling adjacent building blocks, corner elements, and the elements used at window jambs and the like. By having a supply of these elements or units various combinations may be used 40 to effect the desired construction.

The body elements are extruded from non-hygroscopic plastic materials and the joints or coupling elements may be cast or molded from like materials.

The wall 1 of Figure 1 is formed of a plurality of superimposed hollow rectangular building elements or blocks 2 joined by joints or couplings 3. A window jamb is indicated at 4, said jamb being secured in place by rabbeted fittings 5 that fit into the ends of the building elements 2.

Each hollow building element 2 is in the form 55 of a tube of rectangular cross section and is, op-

tionally, provided with trussed stiffening and load sustaining elements 7. Each stiffening element 7 is of a generally rectangular shape, as may be seen from Figure 4, and has two diagonally extending truss members 8-8 extending from one corner to the opposite corner thereof. A hub 9 having an opening 10 is formed at the center or intersection of the truss members 8 for a purpose which will be apparent as this description proceeds. On the outer surface of each one of three or four sides of the load sustaining element 7 two depressions 12-12 are formed. These depressions may be circular in shape and are provided merely to facilitate forming a lock between the load sustaining element and the hollow building element. After the truss member 7 has been positioned within the rectangular hollow building element a hot tool is pressed on the outer surface of the building element 2 opposite each of the depressions 12, to heat the adjacent plastic material to a temperature sufficient to soften it and to force some of it to protrude into the depressions 12. The load sustaining element 7 is thus locked in position within the rectangular building element by the protuberances extending into the depressions 12. This interlocking arrangement is omitted on at least one surface of the building element, which surface is to be on the exposed side of the finished wall. If desired these interlocking projections may be omitted on two opposite surfaces of the block element 2, especially where the tile or building element is to be built into a wall, such as a partition wall, where opposite surfaces of the building element of the wall are exposed. The load sustaining element 7, as previously stated, may be made of plastic, although it is within the purview of the present invention to use other materials, such as steel, where a much greater strength is required.

Figure 3 shows a coupling element 3. The coupling element is of a generally hollow rectangular shape, trussed as are the load sustaining elements 7, and of outside dimensions such as to enable it to fit snugly into the end of a building element 2. A centrally located peripherally extending flange 15 limits the extent to which the coupling element or joint may be inserted into the building element. This flange extends from the outer surface 16 of the joint an amount equal to the thickness of the wall of the building element 2, or it may extend outwardly a slightly lesser amount where it is desired to produce a slight recess at each joint in a course or row on the building. The coupling element is also a load sustaining member and may be made of the same plastic material as are the building elements 2 or, where a greater strength is desired, it may be made of other materials, such as steel.

As shown in Figure 1, the stiffening or load sustaining elements 7 of the various building elements in any one course, and the joints 3, which also act as load sustaining members, are all in vertical alignment with the corresponding load sustaining elements of the other courses. As a result, if any appreciable vertical dead load is to be placed on the wall it is placed in such positions as to be immediately over vertically aligned rows of stiffening or load sustaining elements 3-7.

When the building element 2 is to be used for forming partition walls, which are not subjected to any appreciable vertical load, the load sustaining elements 7 may be omitted.

Each rabbeted fitting 5 is preferably made of plastic, as is the element 2. The fitting 5 consists

of a solid rectangular plastic block 20 having a vertically extending channel 21 formed therein for receiving a window sash 22 and having a rearwardly extending rectangular sleeve 23 integral therewith which fits snugly within the hollow building element. The outside dimensions of the rectangular rabbeted fitting 5 are the same as the outside rectangular dimensions of a building element 2.

Figure 6 shows a corner element. This corner element is a molded or cast hollow plastic box-like structure 30 having rectangular sleeves 31-31 integral therewith. These sleeves fit snugly within the hollow rectangular building elements 2. The length, width and height of the part 30 of the corner element are such as to cause its surfaces to lie flush with the adjacent surfaces of building elements 2 joined thereby.

In the forming of a wall, as shown in Figure 1, the joints between adjacent elements 2 in a given row are, preferably, cemented together, as by coating the sleeve 16 of each coupling element with a plastic cement immediately before the sleeve is inserted into the building element 2. Likewise, the sleeve 31 of each corner element is coated with a plastic cement immediately before the sleeve is inserted into a building element 2. Also, if desired, the top surface of each building element 2 may be coated with a plastic cement immediately before another element is laid thereupon.

While I have shown the top and bottom outer surfaces of the element 2 as perfectly flat, this is not an indispensable part of the present invention. For instance, the top surface of the element 2 may be provided with a longitudinally extending ridge or projection, and the bottom surface may be provided with a similarly located longitudinally extending groove of a size adapted to receive the projection of the subjacent tile or element, in the manner shown in my pending application entitled, "Hollow insulating building block," filed of even date herewith, to which reference may be had.

Reference may now be had to Figure 7 which shows one manner of inserting two or more load sustaining elements 7 into a preformed building element. In this figure there are shown four load sustaining elements 7a, 7b, 7c and 7d of identical construction, except that the central openings 10 of the respective load sustaining elements are of different diameters, that of the element 7a being smallest and the others being of progressively larger diameter. The elements 7a, 7b, 7c and 7d are mounted upon a rod 40 that has projections 41, 42, 43 and 44 thereon. These projections are of different diameters, the projection 41 being of smallest diameter and the projections 42, 43 and 44 being of progressively larger diameter. The projection 41 is of a diameter slightly in excess of the diameter of the central opening 10 in the element 7a and of slightly smaller diameter than the diameter of the opening 10 in the element 7b. The projection 42 is of slightly larger diameter than that of the opening 10 in the element 7b and of less diameter than that of the opening 10 in the element 7c. Likewise, the projection 43 is of a diameter slightly greater than the diameter of the opening in the element 7c and less than the diameter of the corresponding opening in the element 7d. The projection 44 is of a diameter slightly greater than that of the opening 10 in the element 7d. As a result of this arrangement the load sustaining elements 7d, 7c, 7b and 7a may be progressively strung up-

on the rod 40 until they reach the projections 44, 43, 42 and 41, respectively, which limits the extent to which they may be strung on the rod. Thereafter the rod may be pushed or pulled into the element 2 from the right to the left, thereby forcing the load sustaining elements into the building element while maintaining the load sustaining elements a fixed distance apart. When they are thus properly positioned the rod 40 may be withdrawn to the right, thereby withdrawing it from the building element 2. Since the positions of the load sustaining elements within the building element 2 are known, they may be locked in place by forming the depressions 12 previously referred to.

In Figure 7 there is shown one method of positioning the load sustaining elements 7 within the member 2. It is to be understood that the invention is not limited to this particular method as other methods may be used. For instance, the holes 10 in the load sustaining elements 7 may be oval, rather than circular in shape, in which case the holes in all of the load sustaining elements 7 would be of the same size. The projections 41, 42, 43 and 44 on the rod 40 would then be oval projections, all of the same size and slightly less than the size of the oval holes in the load sustaining elements 7. The rod may then be inserted through the holes 10, and by turning the rod through 90° the ends of the major axes of the oval projections 41-44 would coincide with the minor axes of the openings 10 and therefore the projections 41-44 would abut against the respective elements 7a-7d and force those elements in the block 2 to the desired position. Thereafter, to remove the rod it would merely be necessary to turn it through approximately 90° and then withdraw it. As another alternative, the openings 10 may all be circular and all of the same diameter. The rod 40 could be replaced by a slotted tube having a pronged rod therein which could be moved to project through the slots into abutment with the elements 7, or retracted so as not to project through the slots, thus permitting the ready insertion of the elements 7 into the block 2 in the same manner as was described above in connection with the description of Figure 7.

Figure 8 shows a corner joint of a construction different from that of Figure 6. This corner joint differs from that of Figure 6 only in that the sleeves 31-31 of Figure 6 have been omitted. When this is done the corner joint is connected to the rectangular building element by means of couplings 3.

Figure 9 is a transverse sectional view through a building element corresponding to the building element 2, but used at the cornices of the building, or the like. This element is extruded in the same manner as before, and has a flat bottom surface 50, flat top surface 51, flat rear surface 52, and an ornamented front surface 53. Stiffening elements 55, which correspond to the load sustaining element 7 previously described, are mounted in this unit in the same manner as the load sustaining elements 7 are mounted in the unit 2. These stiffening members 55 are of a cross sectional shape the same as that of the interior of the cornice member of Figure 9 and help to retain its shape.

In compliance with the requirements of the patent statutes I have here shown and described a preferred embodiment of my invention. It is, however, to be understood that the invention is not limited to the precise construction here

shown, the same being merely illustrative of the principles of the invention.

What I consider new and desire to secure by Letters Patent is:

- 5 1. A building block comprising a hollow tube of substantially uniform thickness, and a load sustaining element comprising a plate entirely within and extending transversely of the tube, the interior of the tube being of substantially uniform shape lengthwise thereof so that the load sustaining element may be shifted lengthwise of the tube to any desired position therein, the thickness of the element in a direction lengthwise of the tube being a fraction of half 10 of the length of the tube, the upper longitudinally extending surface of the tube being substantially a counterpart of the lower longitudinally extending surface so that a plurality of blocks may be laid one upon another.
- 15 2. A building block comprising a hollow tube of substantially uniform thickness, and a separate load sustaining element entirely within and extending transversely of the tube, the interior of the tube being of substantially uniform shape lengthwise thereof so that the load sustaining element may be shifted lengthwise of the tube to any desired position therein, and means locking the load sustaining element in the tube, the upper longitudinally extending surface of the tube being substantially a counterpart of the lower longitudinally extending surface so that a plurality of blocks may be laid one upon another.
- 20 3. A building block comprising a hollow tube, a load sustaining element comprising a stiffening plate member within and extending transversely of the tube, said tube and said element being both made of a non-hygroscopic plastic material, and spaced apart interlocking means interlocking said tube with said element, the upper longitudinally extending surface of the tube being substantially a counterpart of the lower longitudinally extending surface so that a plurality of blocks may be laid one upon another.
- 25 35 4. A building block comprising a hollow tube, the upper longitudinally extending surface of the tube being substantially a counterpart of the lower longitudinally extending surface so that a plurality of blocks may be laid one upon another, a stiffening plate fitting snugly within the tube, said plate having at least one depression in a surface thereof that is in contact with the inner surface of the tube, and a protuberance formed on the inner surface of the tube and extending into the depression for locking the stiffening plate in the tube.
- 30 40 5. A building element comprising a tube substantially rectangular in cross section, a plurality of spaced stiffening plates within the tube, said plates being separate from and fitting within the tube and said tube being of uniform internal cross section so that the stiffening plates may be located at any desired position therein, and means for locking the plates in position within the tube.
- 35 45 6. A building element comprising a tube adapted to be placed in superimposed relationship with other such tubes, a plurality of spaced stiffening plates within the tube, said plates being separate from and fitting within the tube and said tube being of uniform internal cross section so that the stiffening plates may be located at any desired position therein, and means for locking the plates in position within the tube, said means comprising a plurality of spaced apart protuberances formed on the inner 50 55 60 65 70 75

surface of the tube and being in engagement with the stiffening plates.

7. A building element comprising a tube of uniform cross section throughout its length and having two opposite parallel substantially planar faces each extending parallel to the longitudinal axis of the tube and having an interior opening of the same shape and size throughout the length of the tube, a plurality of spaced stiffening plates within the tube, said plates being separate from the tube so that they may be positioned therein any desired distance apart, and means for locking the plates in position within the tube.

8. A building block comprising a hollow tube having two opposite substantially parallel faces each of which is substantially parallel to the longitudinal axis of the tube, a stiffening plate fitting snugly within the tube, said plate having at least one depression in a surface thereof that is in contact with the inner surface of the tube, and a protuberance formed on the inner surface of the tube and extending into the depression for locking the stiffening plate in the tube.

10

JAMES ROE.
